15 Claims. (Cl. 196—26)

1

This invention relates to a method of producing copper soaps or compounds of water-insoluble organic acids from such acids or from alkali-metal soaps or compounds of such acids. While not so limited, the invention is particularly adapted to such a process of producing cupric naphthenate which may be used in a cyclic process for the treatment of crude petroleum oil for fixing certain sulfur compounds, present in the crude petroleum oil to prevent formation of deleterious sulfur compounds in the products of distillation of the oil.

This application is a division of my application Ser. No. 700,823 filed October 2, 1946.

It is well known that most crude petroleum oils contain sulfur in the form of hydrogen sulfide or in more complex forms, the exact natures of which are not known. When such crudes are distilled, reaction occurs which results in the formation of mercaptans and disulfides, which compounds generally are not found in crude petroleum oils.

In my co-pending application Ser. No. 600,646, Patent No. 2,467,429, filed June 20, 1945, I have disclosed a method for the treatment of crude petroleum oil to stabilize or otherwise modify sulfur compounds, other than hydrogen sulfide, which may be present so that upon subsequent distillation of the crude petroleum oil the sulfur compounds contained therein do not decompose or react to produce mercaptans, disulfides or other deleterious sulfur compounds in the distillates. In accordance with the method disclosed in that application, cupric naphthenate is added to and intimately mixed in relatively small amounts with the crude petroleum oil prior to the distillation or fractionation thereof. The addition of cupric naphthenate to the crude petroleum oil stabilizes the sulfur compounds, other than hydrogen sulfide, contained therein so that upon subsequent distillation or fractionation of the crude petroleum oil they do not react or decompose to form mercaptans and disulfides.

In the process of my aforesaid application, the cupric naphthenate is decomposed during the heat treatment of the crude oil and yields naphthenic acid which passes off with the distillates. Also, any naphthenic acid which is present in the crude petroleum oil, as such, will carry through the distillation or fractionation chamber and pass off with the distillates.

The present invention contemplates a process of producing copper soaps, such as copper naphthenates, in which naphthenic acid such as that resulting from the decomposition of cupric

2

naphthenate in the treatment of crude oil, as described above, or naphthenic acid liberated from crude petroleum oil during the distillation or fractionation thereof is first converted into an alkali-metal naphthenate, such as sodium naphthenate, and the alkali-metal naphthenate so produced, or an alkali-metal naphthenate from any other source, is reacted with a copper salt, preferably in the presence of a small amount of hydrocarbon oil which acts as a solvent for the water-insoluble cupric naphthenate produced as a result of the double decomposition of the sodium naphthenate and copper sulfate.

The process preferably is carried out as a cyclic one in which the cupric naphthenate formed by reaction of the alkali-metal naphthenate with the copper sulfate is used in the treatment of hydrocarbon oils as described above, and the naphthenic acid contained in the distillate from the distillation or fractionation chamber first is reacted with an alkali-metal hydroxide to form an alkali-metal naphthenate which subsequently is reacted with the copper salt to form more cupric naphthenate. Thus, the naphthenic acid liberated during the treatment of the crude petroleum is recovered and re-used.

The present invention also contemplates a process in which the copper product resulting from the decomposition of the cupric naphthenate, during the treatment of the hydrocarbon oil containing the same, is used as a source material for forming the copper salt, which in turn may be used for reaction with the alkali-metal naphthenate to form the cupric naphthenate. Thus, not only is the naphthenic acid liberated during the treatment of the oil recovered and used as one of the materials for forming more cupric naphthenate to be used, but the copper product of the decomposition is used to form the copper salt used in the reaction with the sodium naphthenate. Therefore, the process is cyclic both with respect to copper and naphthenic acid.

For a fuller and more complete understanding of the invention reference is made to the accompanying drawings in which

Fig. 1 is a flow sheet illustrating one method in which the process of the present invention may be carried out in a cyclic manner in connection with the treatment of crude petroleum oil with cupric naphthenate, and

Fig. 2 is a flow sheet of a slightly modified arrangement.

Referring first to Fig. 1, a charge of crude petroleum oil passing through a conduit 1, together with a small amount of cupric naph-

thenate introduced through a conduit 2, is pumped by a pump 3 through a charge heater 4 where the temperature of the crude petroleum oil is raised to its flashing point, for example, about 750° F. The thus heated crude oil, together with the cupric naphthenate contained therein, is then introduced into the lower portion of a fractionation column 5, whereupon the petroleum oil flashes, forming a vapor phase consisting of distillates and naphthenic acid resulting from decomposition of the cupric naphthenate, and a liquid phase consisting of fuel oil which carries the copper product of the decomposition of the cupric naphthenate. The copper product and the fuel oil settle to the bottom of the column and are withdrawn as hereinafter described. The vapor resulting from the flashing of the hot charge of crude oil may be fractionated into as many fractions as desired. As shown in Fig. 1, it is divided into a light gas and gasoline fraction which is withdrawn from the top of the column 5 through a conduit 6, a heavier fraction of light distillates which is withdrawn at a lower level from the column, through a conduit 7, and a still heavier fraction consisting essentially of gas oil which is withdrawn from a still lower portion of the column through a conduit 8. The fractions withdrawn through the conduits 6, 7 and 8 will contain varying amounts of the naphthenic acid resulting from the decomposition of the cupric naphthenate, and, if the crude oil is of the naphthene-base type, from the presence of naphthenic acid present, as such in the original crude oil. However, most of the naphthenic acid will be contained in the gas oil fraction withdrawn through conduit 8. The fractions withdrawn through the conduits 6, 7 and 8 may be passed through condensers 9, 10 and 11 in accordance with the usual practice.

In accordance with the present invention any one or all of the fractions withdrawn through the conduits 6, 7 and 8 may be treated with an alkali-metal hydroxide, preferably molten caustic, to form an alkali-metal naphthenate, which subsequently is converted to cupric naphthenate. As shown in Fig. 1, the gas oil fraction withdrawn through the conduit 8, which contains a relatively large percentage of the naphthenic acid resulting from decomposition of the cupric naphthenate used in the treatment of the oil, is passed through a neutralizer 12 where it is caused to react with an alkali-metal hydroxide, preferably sodium hydroxide, supplied in the form of a concentrated solution of about 45° to 50° Bé. from a container 13 by means of a pump 14 and conduit 15. On introduction of the caustic solution into the neutralizer 12 the water content thereof vaporizes, and leaves the caustic in the molten state. The neutralizer 12 is maintained substantially filled with chains or some inert material which will cause a large surface contact between the molten caustic and the hot oil vapors containing the naphthenic acid. As the hot gas oil vapors and naphthenic acid rise in the neutralizer 12 countercurrent to the downward flowing molten caustic the naphthenic acid contained in them comes into intimate contact with the caustic with the resulting formation of sodium naphthenate and water. The sodium naphthenate which is thus formed has a higher boiling point than the gas oil and settles to the bottom of the neutralizer as a liquid. The amount of sodium hydroxide introduced into the neutralizer 12 is equal to or slightly more or less than the stoichiometric equivalent of the naphthenic acid contained in the gas oil vapors. The pressure in the neutralizer is not

important; it may be that normally prevailing in columns where gas oil vapors are fractionated.

In order to obtain more complete reaction between the caustic and the naphthenic acid, the sodium naphthenate and any unreacted caustic are withdrawn from the bottom of the neutralizer 12 through a conduit 16 and pumped by a pump 17 through a conduit 18 back to the upper portion of the neutralizer through which it thus circulates. The conduit 18 is provided with a valve 19. A conduit 20 is connected to the conduit 18 between the pump 17 and the valve 19 which normally is so adjusted that a relatively small proportion of the sodium naphthenate constantly is withdrawn through the conduit 20. The gas oil freed of the naphthenic acid, and steam resulting from vaporization of the water formed during the reaction between the naphthenic acid and the caustic, and from vaporization of water from the caustic supplied to the neutralizer 12, is withdrawn from the top of the neutralizer through a conduit 21 leading to the condenser 11. The water resulting from the condensation of the steam may be separated in the condenser 11 from the gas oil in any desired manner.

The sodium naphthenate withdrawn through the conduit 20 is introduced into a reaction tank 22 where it is caused to react, at an elevated temperature, preferably about 200° F., with copper sulfate, or other copper salt, such as the nitrate, chloride, etc., in the form of an aqueous solution introduced through a conduit 23 from a supply tank 24. An agitator 25 is provided in the reaction chamber 22 and is operated at a speed sufficient to impart a gentle agitation to the mixture undergoing reaction therein. If the sodium naphthenate withdrawn through the conduit 20 contains any free caustic, it is neutralized before the sodium naphthenate is reacted with the copper sulfate.

In the reaction chamber 22, the sodium naphthenate reacts with the copper sulfate to form sodium sulfate and cupric naphthenate. The sodium sulfate may be withdrawn from the bottom of the reaction chamber 22 through a conduit 26. The cupric naphthenate which is formed is water-insoluble but is oil-soluble. Ordinarily enough of the higher boiling constituents of the gas oil will be condensed and withdrawn from the neutralizer 12 along with the sodium naphthenate by entrainment to dissolve the cupric naphthenate as fast as it is formed in the reaction chamber 22. The solution of cupric naphthenate in the gas oil, being lighter than the aqueous solution of sodium sulfate, will form a supernatant layer on top of the aqueous sodium sulfate and will continuously pass over a launder 27 in the tank 22 and be withdrawn through a conduit 28.

If the copper sulfate solution supplied from the tank 24 is not sufficiently dilute to obtain sufficiently rapid reaction between the sodium naphthenate, additional water may be introduced into the reaction tank 22 through a conduit 29.

The cupric naphthenate withdrawn from the reaction tank 22 through the conduit 28 is cycled back through the conduit 2 and used for the treatment of further amounts of crude petroleum oil in the manner more particularly described in my aforesaid application.

The bottoms from the fractionation column 5 constitute the fuel oil fraction and contain all, or at least most, of the copper product resulting from the decomposition of the cupric naphthenate as described above. The copper in such copper product ordinarily will be in the form of

cuprous sulfide, cuprous oxide, metallic copper, or insoluble copper-sulfur compounds of unknown composition. The bottoms from the fractionation column 5 containing the copper product referred to above is withdrawn through a conduit 30 and passed by means of a pump 31 to a thickener or filter 32, which may be a hot-oil filter, a thickener of the Dorr type or a thickener of filter of any other type which will separate the hot fuel oil from the entrained copper product. The separated fuel oil is withdrawn through a conduit 33 while the recovered copper product is withdrawn from the bottom of the thickener or filter through a conduit 34.

The copper product passing through the conduit 34 is delivered to a treater 35 where it is converted to copper sulfate in any desired manner. This may be done by roasting, treatment with sulfuric acid or a combination of both steps. Ordinarily it is preferred to first roast the copper product to convert the metallic copper content thereof to the oxide, in which form it is more readily acted upon by sulfuric acid. The resulting copper sulfate is withdrawn through conduit 35' and passed to the copper sulfate container 24 for reaction with more sodium naphthenate withdrawn from the neutralizer 12.

If the particular crude petroleum which is being treated is of the naphthene-base type and contains a relatively high proportion of naphthenic acid, the amount of sodium naphthenate formed in the neutralizer 12 may be more than would be desirable to convert to cupric naphthenate for re-use in the system. In such a case, any such excess of sodium naphthenate may be withdrawn through a conduit 36 controlled by a valve 37; or the excess naphthenic acid may be permitted to remain in the distillate, reacting only sufficient of the naphthenic acid with the caustic to form the required amount of sodium naphthenate for subsequent conversion to cupric naphthenate. That may be done by restricting the amount of caustic available for reaction with the naphthenic acid in the neutralizer 12, by by-passing a portion of the hot gas oil vapors through a conduit 8a controlled by a valve 8b. On the other hand, should the amount of naphthenic acid contained in the crude petroleum oil be insufficient to compensate for that lost by removal with lighter fractions not treated for the recovery of the naphthenic acid content thereof, such additional amount of naphthenic acid as may be necessary may be introduced through a conduit 38.

In Fig. 1 only the gas oil fraction withdrawn from the lower portion of the fractionator or distillation column 5 is treated for recovery of the naphthenic acid and its conversion to cupric naphthenate. However, if desired, the fractions withdrawn through the conduits 6 and 7 also could be passed through neutralizers similar to the neutralizer 12 for conversion of the naphthenic acid content thereof to sodium naphthenate which subsequently would be converted to cupric naphthenate as described above, such neutralizers being indicated in dotted lines at 12a and 12b, respectively.

In Fig. 2 there is disclosed a modified form of the invention in which the heated charge of crude petroleum oil containing the cupric naphthenate is first introduced into a flash drum 40. All of the fuel oil formed as a result of the flashing of the crude petroleum, and the copper product resulting from decomposition of the cupric naphthenate, settle to the bottom of the flash

drum, as described in connection with the process as carried out with the apparatus of Fig. 1.

All of the vapors from the flash drum are withdrawn from the top through a conduit 41 and passed through a neutralizer 12' where the naphthenic acid content thereof is reacted with caustic to form sodium naphthenate in the manner described above. The hydrocarbon vapors and steam resulting from vaporization of water produced in the reaction between the caustic and sodium naphthenate is withdrawn from the top of the neutralizer 12' through a conduit 21' and passed into the lower end of a fractionator 42 where they are fractionated into lighter and heavier fractions which are withdrawn through conduits 43, 44 and 45, respectively. Those fractions may be passed through condensers 9', 10' and 11', respectively, as is customary. In all other respects, the process represented by the flow sheet of Fig. 2 is identical with that described above in connection with the flow sheet of Fig. 1, and like reference characters, primed, have been used to designate like parts of the apparatus.

From the foregoing, it will be apparent that the present invention provides a process for producing cupric naphthenate which preferably forms a part of a cyclic process for the treatment of crude petroleum with cupric naphthenate in which provision is made for the recovery of the copper content as well as the naphthenic acid content of the cupric naphthenate treating agent, and their reaction to provide additional cupric naphthenate which may be used for the treatment of additional crude petroleum. When used in connection with such a process for fixing sulfur compounds contained in the crude petroleum oil it has the further advantage of improving the quality of the distillates which are recovered due to the fact that the naphthenic acid and any other organic acids which are present in the distillates are removed.

While the invention has been particularly described in connection with the production of cupric naphthenate from naphthenic acid or sodium naphthenate, it is to be understood that the process is equally applicable to the production of other copper soaps of water-insoluble organic acids which are volatile and subsequently stable at the temperatures to which the oil is heated, such as cupric oleate, or cupric tallate. Thus, if cupric oleate, for example, were used for the fixation of sulfur compounds in the crude oil, oleic acid would result from the decomposition of the cupric oleate in the fractionation column which could be reacted with the caustic in the neutralizer 12 to form sodium oleate, which subsequently would be converted to cupric oleate in the manner described above in connection with conversion of sodium naphthenate to cupric naphthenate.

Also, the process is not necessarily limited to the production of cupric naphthenate or similar cupric salts of water-insoluble organic acids, and would be equally useful for the production of cuprous naphthenate or other cuprous salts of water-insoluble organic acids. In order to produce cuprous naphthenates or other cuprous salts of water-insoluble organic acids it is only necessary that a heater 39, through which the cupric naphthenate may be bypassed and heated to a temperature sufficient to cause its reduction to cuprous naphthenate, be inserted in the conduit 28.

While the charging stock introduced through the conduit 1 has been referred to as crude petro-

leum oil; it is to be understood that it might be any other stock which it is desired to treat with cupric naphthenate for the fixation of sulfur compounds contained therein.

Various changes may be made in the procedure without departing from the invention or sacrificing any of the advantages thereof.

I claim:

1. In the process of treating petroleum oil with a copper soap of a water-insoluble organic acid for the fixation of sulfur compounds contained therein in which the copper soap is introduced into the oil and the oil subsequently is subjected to heat treatment and the liberation of vapors containing the organic acid resulting from decomposition of the copper soap; the improvement which comprises separately withdrawing the copper compound and the liberated vapors containing the organic acid resulting from the decomposition of the copper soap from the zone of heat treatment passing withdrawn vapors into intimate contact with caustic with resultant formation of the sodium soap of the acid, and reacting the sodium soap so formed with a copper salt to form the corresponding cupric soap of the acid, and using the thus formed cupric soap as the source material of the copper soap used in the treatment of further amounts of oil.

2. In the process of treating petroleum oil with a copper naphthenate for the fixation of sulfur compounds contained therein in which the copper naphthenate is introduced into the oil and the oil subsequently is subjected to heat treatment and the liberation of vapors containing naphthenic acid resulting from decomposition of the copper naphthenate; the improvement which comprises separately withdrawing the copper compound and the liberated vapors containing the naphthenic acid resulting from the decomposition of the copper naphthenate from the zone of heat treatment passing withdrawn vapors into intimate contact with caustic with resultant formation of sodium naphthenate, reacting the sodium naphthenate so formed with a copper salt to form cupric naphthenate and using the thus formed cupric naphthenate as the source material of the copper naphthenate used in the treatment of further amounts of oil.

3. In the process of treating petroleum oil with a cupric soap of a water-insoluble organic acid for the fixation of sulfur compounds contained therein in which the cupric soap is introduced into the oil and the oil subsequently is subjected to heat treatment and the liberation of vapors containing the water-insoluble organic acid resulting from decomposition of the cupric soap; the improvement which comprises separately withdrawing the copper compound and the liberated vapors containing the water-insoluble organic acid resulting from the decomposition of the cupric soap from the zone of heat treatment passing withdrawn vapors into intimate contact with caustic with resultant formation of the sodium soap of the acid, and reacting the sodium soap of the acid so formed with copper sulfate to form the corresponding cupric soap, and returning the thus formed cupric soap for the treatment of further amounts of petroleum oil.

4. In the process of treating petroleum oil with a cupric soap of a water-insoluble organic acid for the fixation of sulfur compounds contained therein in which the cupric soap is introduced into the oil and the oil subsequently is subjected to heat treatment and the liberation of vapors containing a water-insoluble organic acid result-

ing from decomposition of the cupric soap; the improvement which comprises separately withdrawing the copper compound and the liberated vapors containing the water-insoluble organic acid resulting from the decomposition of the cupric soap from the zone of heat treatment passing withdrawn vapors into intimate contact with molten caustic with resultant formation of the sodium soap of the acid, and reacting the sodium soap of the acid so formed with a copper salt to form the corresponding cupric soap, and returning the thus formed cupric soap for the treatment of further amounts of petroleum oil.

5. In the process of treating petroleum oil with a cupric soap of a water-insoluble organic acid for the fixation of sulfur compounds contained therein in which the cupric soap is introduced into the oil and the oil subsequently is subjected to heat treatment and the liberation of vapors containing the water-insoluble organic acid resulting from decomposition of the cupric soap; the improvement which comprises separately withdrawing the copper compound and the liberated vapors containing the water-insoluble organic acid resulting from the decomposition of the cupric soap from the zone of heat treatment passing the withdrawn vapors into intimate contact with caustic with resultant formation of the sodium soap of the acid; reacting the sodium soap of the acid so formed with a copper salt in an aqueous medium in the presence of an oil in which the cupric soap of the acid is soluble, whereby the cupric soap formed is taken up by and dissolves in the oil and the resulting solution forms a supernatant layer on the aqueous medium, and separating the oil solution of the cupric soap from the aqueous medium, and returning the separated oil solution of the cupric soap for treatment of further amounts of petroleum oil.

6. In the process of treating petroleum oil with a copper soap of a water-insoluble organic acid for the fixation of sulfur compounds contained therein in which the copper soap is introduced into the oil and the oil subsequently is subjected to heat treatment with the liberation of vapors containing the water-insoluble organic acid resulting from decomposition of the copper soap and a copper compound; the improvement which comprises converting the copper compound to a copper salt, passing liberated vapors containing the water-insoluble organic acid into intimate contact with caustic with resultant formation of the sodium soap of the acid, reacting the sodium soap so formed with the copper salt formed from the separated copper compound to form the corresponding cupric soap, and using the thus formed cupric soap as the source material of the copper soap used in the treatment of further amounts of petroleum oil.

7. In the process of treating petroleum oil with a copper soap of a water-insoluble organic acid for the fixation of sulfur compounds contained therein in which the copper soap is introduced into the oil and the oil subsequently is subjected to heat treatment with the liberation of vapors containing the water-insoluble organic acid resulting from decomposition of the copper soap and a copper compound; the improvement which comprises converting the copper compound to a copper salt, passing liberated vapors containing the water-insoluble organic acid into intimate contact with molten caustic with resultant formation of the sodium soap of the acid, reacting the sodium soap so formed with the copper salt formed from the separated copper compound to

form the corresponding cupric soap, and using the thus formed cupric soap as the source material of the copper soap used in the treatment of further amounts of petroleum oil.

8. In the process of treating petroleum oil with cupric naphthenate for the fixation of sulfur compounds contained therein in which cupric naphthenate is introduced into the oil and the oil subsequently is subjected to heat treatment with the liberation of vapors containing naphthenic acid resulting from decomposition of the cupric naphthenate and a copper compound; the improvement which comprises converting the copper compound to a copper salt, passing liberated vapors containing naphthenic acid into intimate contact with caustic with resultant formation of sodium naphthenate, reacting the sodium naphthenate so formed with the copper salt formed from the separated copper compound to form cupric naphthenate, and returning the cupric naphthenate for the treatment of further amounts of petroleum oil.

9. In the process of treating petroleum oil with a copper soap of a water-insoluble organic acid for the fixation of sulfur compounds contained therein in which a copper soap is introduced into the oil and the oil subsequently is subjected to heat treatment with the liberation of vapors containing the water-soluble organic acid resulting from decomposition of the copper soap and a copper compound; the improvement which comprises passing liberated vapors containing the water-insoluble organic acid into intimate contact with caustic with resultant formation of the sodium soap of the acid, converting the copper compound to a copper salt, reacting the sodium soap with the copper salt formed from the separated copper compound in an aqueous medium in the presence of an oil in which the cupric soap of the water-insoluble organic acid is soluble, whereby the cupric soap formed is taken up by and dissolves in the oil and the resulting solution forms a supernatant layer on the aqueous medium, separating the oil solution of the cupric soap from the aqueous medium, and using the thus separated oil solution of the cupric naphthenate as the source material of the copper soap used in the treatment of further amounts of petroleum oil.

10. In the process of treating petroleum oil with a copper soap of a water-insoluble organic acid for the fixation of sulfur compounds contained therein in which the copper soap is introduced into the oil and the oil subsequently is subjected to heat treatment with the liberation of vapors containing the water-insoluble organic acid resulting from decomposition of the copper soap and a copper compound; the improvement which comprises passing liberated vapors containing the water-insoluble organic acid into intimate contact with caustic with resultant formation of the sodium soap of the acid, converting the copper compound to copper sulfate, reacting the sodium soap, at an elevated temperature and with agitation, with the copper sulfate formed from the separated copper compound in an aqueous medium in the presence of an oil in which the cupric soap of the acid is soluble, whereby the cupric soap formed is taken up by and dissolves in the oil and the resulting solution forms a supernatant layer on the aqueous medium, and using the thus separated oil solution of the cupric naphthenate as the source material of the copper

soap used in the treatment of further amounts of petroleum oil.

11. In the process of treating petroleum oil with a copper soap of a water-insoluble organic acid for the fixation of sulfur compounds contained therein in which the copper soap is introduced into the oil and the oil subsequently is subjected to heat treatment and the liberation of vapors containing the water-insoluble organic acid resulting from the decomposition of the copper soap, the improvement which comprises withdrawing the copper compound resulting from the decomposition of the copper soap, separately withdrawing all of the oil vapors containing the water-insoluble organic acid, passing the separated vapors into intimate contact with caustic with resultant conversion of the water-insoluble organic acid to the sodium soap thereof, separating the oil vapors freed from the water-insoluble organic acid, fractionating the separated oil vapors, reacting the sodium soap with a copper salt to form the corresponding cupric soap and using the thus formed cupric soap as the source material of the copper soap used in the treatments of further amounts of oil.

12. In the process of treating petroleum oils with cupric naphthenate for the fixation of sulfur compounds contained therein in which cupric naphthenate is introduced into the oil and the oil subsequently is subjected to heat treatment with the liberation of vapors containing naphthenic acid resulting from the decomposition of the cupric naphthenate; the improvement which comprises withdrawing the copper compound resulting from the decomposition of the cupric naphthenate, separately withdrawing all of the oil vapors containing the naphthenic acid, passing the separated vapors into intimate contact with caustic with resultant conversion of the naphthenic acid to sodium naphthenate, separating the oil vapors freed of the naphthenic acid, fractionating the separated oil vapors, reacting the sodium naphthenate with a copper salt to form cupric naphthenate and returning the cupric naphthenate for the treatment of further amounts of petroleum oil.

13. In the process of treating petroleum oils with a cupric soap of a water-insoluble organic acid for the fixation of sulfur compounds contained therein in which the cupric soap is introduced into the oil and the oil subsequently is subjected to heat treatment with the liberation of vapors containing the water-insoluble organic acid resulting from the decomposition of cupric soap; the improvement which comprises withdrawing the copper compound resulting from the decomposition of the cupric soap, separately withdrawing all of the oil vapors containing the water-insoluble organic acid, passing the separated vapors into intimate contact with caustic with resultant conversion of the water-insoluble organic acid to the sodium soap thereof, separating the oil vapors freed of the naphthenic acid, fractionating the separated oil vapors, reacting the sodium soap with a copper salt in an aqueous medium in the presence of an oil in which cupric soap of the acid is soluble, whereby the cupric soap formed is taken up by and dissolves in the oil and the resulting solution forms a supernatant layer on the aqueous medium, separating the oil solution of the cupric soap from the aqueous medium, and returning the separated oil solution of the cupric

soap for the treatment of further amounts of petroleum oil.

14. In the process of treating petroleum oils with a copper soap of a water-insoluble organic acid for the fixation of sulfur compounds contained therein in which the copper soap is introduced into the oil and the oil subsequently is subjected to heat treatment with the liberation of vapors containing the water-insoluble organic acid resulting from the decomposition of the copper soap; the improvement which comprises withdrawing the copper compound resulting from the decomposition of the copper soap, separately withdrawing all of the oil vapors containing the water-insoluble organic acid, passing the separated vapors into intimate contact with molten caustic with resultant conversion of the water-insoluble organic acid to the sodium soap thereof, separating the oil vapors freed of the naphthenic acid, fractionating the separated oil vapors, reacting the sodium soap at an elevated temperature and with agitation, with a copper salt in an aqueous medium in the presence of an oil in which the cupric soap of the acid is soluble, whereby the cupric naphthenate formed is taken up by and dissolves in the oil and the resultant solution forms a supernatant layer on the aqueous medium, separating the oil solution of the cupric soap from the aqueous medium, and using the oil solution of the cupric soap as the source material for the copper soap used in the treatment of further amounts of oil.

15. In the process of treating petroleum oils with cupric naphthenate for the fixation of sulfur compounds contained therein in which cupric naphthenate is introduced into the oil and the oil subsequently is subjected to heat treat-

ment with the liberation of vapors containing naphthenic acid resulting from the decomposition of the cupric naphthenate and the formation of a copper compound; the improvement which comprises separating the copper compound and converting it to copper sulfate, passing all of the oil vapors containing the naphthenic acid into intimate contact with caustic with resultant conversion of the naphthenic acid to sodium naphthenate, separating the oil vapors freed of the naphthenic acid, fractionating the separated oil vapors, reacting the sodium naphthenate, at an elevated temperature and with agitation, with copper sulfate formed from the separated copper product, in an aqueous medium in the presence of an oil in which cupric naphthenate is soluble, whereby the cupric naphthenate formed is taken up by and dissolves in the oil and the resultant solution forms a supernatant layer on the aqueous medium, separating the oil solution of the cupric naphthenate from the aqueous medium, and returning the oil solution of cupric naphthenate for the treatment of further amounts of petroleum oil.
